UNITED STATES PATENT OFFICE

CHARLES S. BARON, OF TIFFIN, OHIO

FOOD CONTAINER AND CLOSURE THEREFOR

Application filed July 17, 1929. Serial No. 378,984.

My present invention relates particularly to glass jars or other containers that are adapted to hold either dry or liquid substances.

- 5 6 It has for its chief object, among other things, the production of such a device having effectual but simple means for closing the same, and preferably means for hermetically sealing it.
- 20 20 What constitutes my invention will be hereinafter described in detail and succinctly defined in the appended claims.

In the accompanying drawings, which illustrate my invention in a present preferred 25 form of embodiment,

Figure I is a side elevation of a portion of a container made of glass, with its lid or closure attached, and in open position.

Figure II is a diametrical vertical section 20 of the same but with lid closed.

Figure III is a top plan view of the subject matter of Figure I, with the lid closed.

Figure IV is a view, similar to Figure II, showing a modification of the sealing means.

25 Figures V and VI are detail views, showing, respectively, two modifications of the outer surface of the neck 2.

Figure VII is a similar detail showing a variation of the angle of the rim of the lid.

30 Referring to the numerals on the drawings, 1 indicates the body of a container which may be made of glass or of any other suitable material, and of any desired shape, size, and dimensions.

35 The body 1 is provided with a neck 2, which surrounds and defines its mouth, and whose outer periphery consists preferably of a vertically narrow annular zone 3 that is slightly conical or tapered upwardly about its vertical axis. The zone 3 is preferably provided with a peripheral depression or groove 4 to accommodate within it a snugly fitting elastic ring gasket. The groove 4 is flat in cross-section, and the gasket, indicated by the numeral 5, is or becomes by use slightly conical so, at least, as to fit smoothly into it and so as to present an outer surface that is substantially flush with the outer face of the zone. This is the present preferred form of 40 groove and gasket, but a narrow groove 7

having its bottom curved in cross-section to accommodate a gasket consisting of an elastic grommet 8 whose outer face projects a little beyond the face of the zone 3, as shown in Figure IV, may be substituted therefor if 55 desired. Either of the gaskets 5 or 8 is made, preferably, of yielding india rubber, but may be made of any like material that may be found suitable for the purpose.

The closure for the container consists, 60 preferably, of a metal lid 9, which is provided with a rim 10 that is conformable to the shape and dimensions of the zone 3. The rim 10 may be slightly conical in cross-section, conformably to the conical shape of 65 the zone 3, as shown in Figure VII, but its angle of inclination may be a little greater than that of the said zone, and its diameter a little less than the longest outside diameter of the zone. The outside diameter 70 of the zone 3 and the inside diameter of the rim 10 are such, relatively to each other, that the smooth edge 12 at the bottom of the rim begins to make contact with the face of the gasket 5 at about or a little above the medial 75 circumferential line of the latter when the lid 9 is applied with pressure to the neck 2. In consequence of the relative diameters, as above described, of the rim 10 and the neck-supported gasket 5, continued application of 80 pressure tending to force the edge 12 of the rim 10 down upon the said gasket, will compress the gasket, with sealing effect between the engaging surfaces of the said members. Also the relationship of the diameters 85 aforesaid, will prevent the edge 12 from passing over the face of the zone 3 beyond the width of the gasket 5, and will, therefore, maintain at all times an effective yielding contact between the edge 12 and the 90 gasket.

In respect to the grommet 8, if it be substituted for the gasket 5, the cooperation between it and the rim 10 is substantially the same as that just described, except that the 95 inner face of the rim slips over the contacting face of the grommet with compressing and sealing effect thereupon.

If, instead of having different angles of inclination, as aforesaid, the angles of the 100

zone 3 and of the interior of the rim 10 are substantially conformable, as it has been specified they may be, the gasket 5 must project slightly beyond the surface of the zone 5 3 in order to make yielding contact with the inner face of the rim 10. In such case, there may be employed for holding the rim 10 and gasket 5 in sealing contact, any sort of suitable latch mechanism, the use of which may 10 be ordinarily dispensed with when the angles of inclination of the zone 3 and rim 10 are different.

In Figures V and VI, respectively, examples of modified outer faces of the neck 2 are 15 shown; and in Figure VII a modified angle of the rim 10.

The lid 9 may be wholly separable and detachable from the container, but I prefer to operatively unite the container and lid by a 20 suitable hinge connection. With that end in view, I provide, preferably at or near the base of the neck 2, a groove 15 that is substantially parallel to the groove 4, or especially the groove 7, which it closely resembles. A ring clip 16, being made preferably 25 of a section of spring wire, and selected of a length and gauge to snugly fit within the groove 15, affords a convenient and serviceable fixed member for the proper assembling 30 together of the lid and the container in hinged relationship.

In that regard, it should be observed that the mode of application of the lid 9 upon the neck 2 in utilizing the former as a practicable closure to the container is substantially the same in any case, irrespective of whether the lid be separate from or fastened to the container.

The said mode of application in either instance requires, to a considerable degree, freedom of movement of the lid in order to permit its proper adjustment with proper sealing effect upon the neck. Consequently, it is of importance, in respect to the production 40 of a saleable article, to provide means of hingedly uniting a container and its lid with such looseness in the hinge connection between the parts, as will afford the aforesaid requisite freedom of adjustment of the lid to the neck of the container, and will combine therewith such mechanical fitness, through the proper adaptation of part to part and function to function, as will prove 45 attractive to the trade.

50 The foregoing observation is deemed to be not so obvious as to be out of place herein, because it may obtain due recognition that the problem in the present instance is materially different from that of merely effecting a loose hinge connection, as might, perhaps, without explanation, appear to be the case.

In view of the last preceding observation, 55 it is now further specified that, by preference, the ring clip 16 is provided, substan-

tially at a point diametrically opposite its adjacent ends 17 and 18 with a pintle-offset 20 that is disposed substantially well beyond the periphery of the neck 2 and which affords a suitably positioned support for a 70 single elongated knuckle 21 on one side of a hinge plate 22.

For the special purpose of affording a favorable means of connection between it and the other side of the hinge plate 22, the rim 10 of the lid is provided with an everted outside annular flange 23, consisting of an extension of the metal of the lid beyond the smooth edge 12 thereof, said edge being preferably formed by the bending of the metal 80 of the lid to constitute the flange 23.

The flange 23 not only imparts to the lid a hat-shaped appearance that gives a pleasing finish to the lid, the outer edge of it being preferably edged by a downwardly bent bead, but it is wide enough to extend over the ring clip 16 far enough to afford for it, in effect, a protecting covering. Moreover, the flange 23 affords, in effect, a sufficient handle for manipulating the lid in the operation of opening it, no other provision for the purpose being necessary.

The outer edge of the flange 23 and that of the pintle of the offset 20 are substantially in the same vertical plane, and the width of the said flange is sufficient to accommodate two coaled slits 25 and 26 whose common axis is substantially parallel with that of the said pintle. The slits 25 and 26 are adapted to accommodate, respectively, two metal strips projecting from the side of the plate 22 opposite to the knuckle 21.

Said strips being passed, respectively, through said slits are thereafter bent, with permanent flexure, to form knuckles 27 and 28 around coaxial single pintle members 29 and 30 which the slits 25 and 26 define in the flange 23.

The shackle effect of the plate 22 and its knuckles, in combination with their respective pintle members 29 and 30 and the pintle of the offset 20, constitutes a hinge connection which answers all requirements demanded of it in use upon my container. That is to say, it permits all the freedom of adjustment that is necessary for the cooperative accommodation of the rim 10 of the lid 9 to the neck 2. Moreover, it is designed and adapted to effect a substantially even movement in the opening and closing of the lid 9, without that objectionable wobbling tendency therein against which provision should be made in order to produce a commercially attractive article.

The operation of my device will, it is believed, be understood by one skilled in the art without necessity for further description. It is deemed, however, proper to add that the specified combination with the lid 9 of a neck 2 without a gasket of any sort, possesses in

itself utility in connection with containers which do not require the sealing effect which is afforded by a yielding gasket and engaging rim 10.

5 What I claim is:

1. The combination with a container body, and a neck surrounding the mouth thereof, of a ring embedded in an annular depression provided for it in the outside of the neck, a
10 pintle-offset formed in the ring, a lid, and a hinge member pivoted to the lid and to said offset, respectively.

15 2. The combination with a container body, and a neck surrounding the mouth thereof, of a ring embedded in an annular depression provided for it in the outside of the neck, a
pintle-offset formed in the ring, a flange defined hat-shaped lid, and a hinge member pivoted to the flange of the lid and to the
20 offset, respectively.

In testimony whereof, I have hereunto set
my hand.

CHARLES S. BARON.
